UNITED STATES PATENT OFFICE.

JAMES H. TOWAN, OF CHARLESTOWN, MASSACHUSETTS, ASSIGNOR OF ONE-HALF TO ABRAM KEACH, OF SAME PLACE.

GAS-LIGHTING APPARATUS.

SPECIFICATION forming part of Letters Patent No. 280,689, dated July 3, 1883.

Application filed February 2, 1883. (No model.)

To all whom it may concern:

Be it known that I, JAMES H. TOWAN, of Charlestown, county of Suffolk, State of Massachusetts, have invented an Improvement in 5 Gas-Lighting Apparatus, of which the following description, in connection with the accompanying drawings, is a specification, like letters on the drawings representing like parts.

My invention, relating to an automatic gas 10 lighting and extinguishing apparatus, is embodied in an apparatus of that class in which a valve controlling the flow of gas to the burner is operated by electro-magnets, one for opening and another for closing the said 15 valve, the one for opening it also operating a circuit-breaker in its own circuit to produce sparks for lighting the gas.

This invention has for its object to make the apparatus more reliable in operation and 20 simpler and less expensive in construction than those heretofore in use; and it consists, mainly, in making the armatures of the magnets by which the valves are operated independent of one another.

Figure 1 is a side elevation of a burner and 25 its lighting and extinguishing mechanism embodying this invention with the inclosing-case removed; Fig. 2, a front elevation thereof, showing the magnet for opening the valve and 30 operating the circuit-breaker; Fig. 3, a vertical section on line *x x*, Fig. 2; Fig. 4, a vertical section on line *y y*, Fig. 1, and Fig. 5 a horizontal section.

The burner *a*, of any usual construction, is 35 screwed upon the valve-containing or socket piece *b*, which is made of a cylinder of solid metal, threaded at its upper end to receive the burner, and bored and threaded at its lower end, as shown at 2, so as to enable it to 40 be mounted upon a pipe or fixture in the usual manner. The socket-piece *b* is bored longitudinally at its upper end, as shown at 3, nearly through to the socket 2 at the lower end of the piece *b*, to afford a passage for the 45 gas to the burner, and the metal of the piece *b* between the passages or sockets 2 3 is bored transversely to afford a tapering socket for the valve *c*, shown as a tapering plug having a portion of its side removed, as shown at 4,

so that it controls by a slight rocking movement the passage or port *d*, which is long in the direction of the valve-socket and very narrow, so that a sufficient area is afforded for the flow of gas, although only a very small rotary movement of the valve is required to 50 open and close the said passage. The smaller end of the valve *c* extends out beyond the side of the piece *b*, and is provided with an annular groove, 5, which receives a spring, *e*, by which the valve is drawn into its socket, so 55 as to maintain a tight fit therein. The valve is provided with an actuating arm or crank, *f*, engaged and operated by arms *h h'*, connected with the armatures *i i'* of the extinguishing and lighting magnets *k k'*, the said armatures 60 being independent of one another, but mounted upon a common pivot, *m*, as best shown in Fig. 5. One electrode of the extinguishing-magnet *k* is connected with the metal of the burner and gas-pipes, constituting a ground, 65 while the other electrode is connected by wire 6 with a key or circuit-closer for applying a battery when desired to magnetize the magnet *k*, and thus cause it to attract its armature *i*, and thus, by the arm *h* and crank *f*, rotate the valve 70 *c*, so as to interrupt the flow of gas and put out the light. One electrode of the lighting-magnet *k'* is connected by wire 7 with a key for applying a battery, and the other electrode is connected by wire 8 with a fixed contact-piece or electrode, *n*, insulated from the burner and forming one portion of a circuit-breaker, the other movable or vibrating portion or electrode, *o*, of which is electrically connected with the frame-work or gas-fixture and 75 ground, and has a longitudinal movement to and from the piece *n*, it being acted upon by a spring, *p*, which normally keeps it in contact with the piece *n*, thus completing the circuit of the magnet *k'* when the proper key is 80 closed. When the circuit of the magnet *k'* is closed or connected with the battery its armature *i* is attracted, and, by the arm *h'*, acts on the crank *f* of the gas-valve *c*, throwing the 85 said valve, so as to permit the gas to flow, and just before the said armature reaches the poles of its magnets it engages the movable electrode *o* of the circuit-breaker by the project- 90 95

ing pin or shoulder r , and, overcoming the spring p , moves the said electrode o away from the electrode n , thus breaking the circuit and producing a spark in the gas issuing from the burner and igniting it in the usual manner. The electrode o is automatically vibrated by the armature i' and spring p , thus producing a series of sparks as long as the battery is connected with the magnet; but the vibration of the armature does not produce any effect on the valve c to disturb the flow of the gas, owing to the fact that it is wholly independent of the armature i of the extinguishing-magnet k , and the arms h h' are not positively connected with the crank f , but merely press upon its opposite sides, so that each one acts only when its corresponding armature is attracted.

I claim—

The combination, with the burner and gas-valve provided with an actuating-crank, of lighting and extinguishing electro-magnets and their independently-pivoted armatures, each provided with an arm adapted to operate upon the said crank independently of the other, substantially as described. 20 25

In testimony whereof I have signed my name to this specification in the presence of two subscribing witnesses.

JAMES H. TOWAN.
